UNITED STATES PATENT OFFICE.

DAVID S. WILLIAMS, OF PHILADELPHIA, PENNSYLVANIA, ASSIGNOR
OF ONE-HALF TO WILLARD C. HOSBACH, OF PHILADELPHIA, PENN-
SYLVANIA.

LANTERN..

SPECIFICATION forming part of Letters Patent No. 794,907, dated July 18, 1905.

Application filed July 13, 1903. Serial No. 165,216.

To all whom it may concern:

Be it known that I, DAVID S. WILLIAMS, a citizen of the United States, residing at Philadelphia, in the county of Philadelphia and State 5 of Pennsylvania, have invented certain new and useful Improvements in Lanterns, of which the following is a specification.

My invention relates to improvements in lanterns; and it consists in devices whereby the wick may be conveniently raised and lowered from the outside, making it unnecessary to remove the oil-reservoir or to otherwise open the lantern, as is required with common forms, which cause considerable annoyance 15 to railroad men and watchmen during cold or windy weather.

My invention will be more fully understood by reference to the accompanying drawings, in which—

20 Figure 1 illustrates a side elevation of a lantern constructed in accordance with my invention. Fig. 2 represents a horizontal section of the same, taken on a line indicated at 22 in Fig. 1. Fig. 3 indicates a vertical section of the oil-reservoir and burner, showing the manner of securing the burner against turning. Fig. 4 is a detached perspective view of the locking-spring. Fig. 5 represents a view similar to Fig. 3 with a modified 25 arrangement of gears for turning the wick-stem, and Fig. 6 illustrates a still further modified type in which the round spiral worm-gear of Fig. 5 is replaced by a flat-surface worm or snail wheel, and Fig. 7 illustrates a 30 modification in which a flexible shaft is made to perform the same service as the gear-wheel referred to.

Referring to the reference-letters of the drawings, A represents the frame of the lantern, B the oil-reservoir, and C and C', respectively, the burner and wick.

The burner C is provided with the usual wick-stem C², which is fitted with star-wheel C³ C³ to move the wick, the stem being turned 45 ordinarily by a knurled disk at the outer end of the wick-stem. My object, as may be seen, is to dispense with this disk and provide a mechanism by which the stem may be operated from without the lantern, which object

I accomplish as follows: As will be seen in 50 Figs. 1, 2, and 3, I provide the wick-stem C² with a bevel-gear C⁴, which is adapted to mesh with a similar gear C⁵ on a vertical shaft C⁶, which is also provided with a knurled operating-knob C⁷, by which the shaft and its 55 connecting parts may be turned.

The shaft C⁶ may, if desired, be secured to the outside of the reservoir B; but, as shown in the drawings, I prefer to have it guided in a tube D, which passes through the oil-reservoir and is secured by solder or other well-known means to the top and bottom thereof.

In order to provide means whereby the gears C⁴ and C⁵ may be caused to be engaged with each other when the burner-head C is in 65 position and to disengage the gears when it is desired to remove the burner-head, I provide the following expedient:

On top of the oil-reservoir I secure a curved leaf-spring E, which is held in place by rivets e e. This spring has a hole or opening e', through which passes the shaft C⁶, and an upward-turned recessed end e², which engages the shaft C². Thus it will be seen that the spring E by pressing upward against the 70 hub of the gear C⁵ will always tend to keep the said gear and its corresponding gear C⁴ in mesh, while at the same time the upturned notched or recessed end e² of the spring engages the shaft C² and locks it against turning. When it is desired, however, to remove the burner-head, which, as will be seen, is threaded to the top of the oil-reservoir in the 75 well-known manner, it is only necessary to pull down the knob C⁷, as shown by dotted 80 line in Fig. 3, against the action of the spring E, when the burner-head may be quickly removed and afterward readjusted.

As my invention is not limited to the specific means for carrying out the same, I have 90 in addition to the form just described shown several examples of analogous forms or modifications—as, for instance, in Fig. 5 I illustrate a method of turning the stem C² from the shaft C⁶ by the interposition of a worm F and 95 a worm-wheel F'. In Fig. 6 the same is accomplished by substituting a flat worm or snail F² and causing it to engage the worm-

wheel F' from below, thus making it easier to bring these elements into and out of engagement, and in Fig. 7 I have shown the stem C² and shaft C' united by a coil or flexible shaft G, which may be detachably secured at one or the other of its ends, or, if desired, at both of its ends, in any desired manner.

Having described my invention, what I claim, and desire to secure by Letters Patent, is—

1. In a lantern, the combination with the oil-reservoir, of a burner-head mounted thereon and provided with a wick-stem, an operating-rod guided upon the oil-reservoir, and means serving to normally hold said rod in operative engagement with the wick-stem, said means also engaging the wick-stem to prevent the burner-head from turning.
- 15

2. In a lantern, a burner-head provided with a wick-operating stem, a gear-wheel on said stem, an oil-reservoir, a rod guided upon said reservoir provided at one end with an operating-knob and at the other with a gear-wheel, which latter is adapted to engage the one first-mentioned gear, and a spring-clip to cause said gears to engage with yielding pressure and to engage the stem of the wick-operating mechanism to prevent the burner from turning, substantially as specified.

In testimony whereof I affix my signature in presence of two witnesses.

DAVID S. WILLIAMS.
